CHAIR SEAT OR THE LIKE

Kim Yamasaki, Lombard, Ill., assignor to Brunswick Corporation, Chicago, Ill., a corporation of Delaware

Filed Sept. 24, 1963, Ser. No. 76,747

Term of patent 14 years

(Cl. D15—8)

FIG. 1 is a front perspective view of a chair seat or the like embodying my new design;

FIG. 2 is a rear perspective view thereof;

FIG. 3 is a side elevational view thereof; and

FIG. 4 is a central vertical sectional view thereof.

The dominant features of the design are shown in full lines on the drawing.

I claim:

The ornamental design for a chair seat or the like, as shown and described.
